CLAIM

I claim the ornamental design for a swivel organizer, as shown and described.

DESCRIPTION

FIG. 1 is a perspective view of my new design for a swivel organizer;

FIG. 2 is a perspective view of my new design for a swivel organizer with the top portion slightly rotated;

FIG. 3 is a side perspective view thereof with side and back doors open, the other side perspective view being a mirror image of that shown;

FIG. 4 is a front elevation view thereof with all doors closed;

FIG. 5 is a right side elevation view thereof with all the doors closed;

FIG. 6 is a rear elevation view thereof with all the doors closed;

FIG. 7 is a left side elevation view thereof with all the doors closed;

FIG. 8 is a top plan view thereof; and,

FIG. 9 is a bottom plan view thereof.

The broken lines shown in the drawings are for illustrative purposes only and form no part of the claimed design.

1 Claim, 8 Drawing Sheets
